UNITED STATES PATENT OFFICE.

JOSEPH GRECO, OF NEW YORK, N. Y.

GAME

Application filed August 10, 1922. Serial No. 580,823.

To all whom it may concern:

Be it known that I, JOSEPH GRECO, a citizen of the United States, residing at the city of New York, borough of Manhattan, in the county of New York and State of New York, have invented certain new and useful Improvements in Games, of which the following is a specification.

This invention relates to games and toys and has particular reference to that type of games in which a game board or field is provided with a series of stations or goals designed to be reached in succession by the several competing players, each of whom will employ one or more disks or the like, referred to hereinafter as men.

Among the objects of the invention is to provide game board, and by the term board as used herein I wish to be understood as covering any suitably arranged field irrespective of its construction or size, having arranged thereon in staggered relation a series of stations or goals suitably identified and having associated therewith other stations to be observed in the competitive playing of the game.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawing which shows a plan view of a preferred embodiment of the invention.

Referring now more specifically to the drawing I show a board of rectangular form upon which are formed or drawn in any suitable manner two concentric circles A and B, the latter of which is inscribed in the periphery of the board. These two circles bound a circular space C and within this space is a central circle D.

At the corners of the rectangular board I arrange starting points E, E', F, and F', the points similarly lettered being similarly colored.

Within the circular space C are formed a circular series of equally spaced stations G, hereinafter termed dwells, each of which is preferably colored blue and red corresponding to the respective starting points E and F. These dwells are indicated as of eight in number, and adjacent to the inner

end of each and within the central circle D is a station represented as of circular form at H, these several stations being numbered from 1 to 8 inclusive but in a staggered relation across the board or circle D, and adjacent to the center of this central circle are two other stations H', numbered 9 and 10, these two stations being externally tangent to a small circle or station I, known as "out".

Indicated in connection with the board are a series of men J differently colored, as for example red, blue, orange, and green, for use by as many different players.

It will be understood that the rules or directions for playing this game may be variously established according to the ages or individual inclinations of the contestants, but for a suggestion of such directions and to serve as a guide in an understanding of the board illustrated I would outline the following rules or directions, it being understood that as many players as may desire to engage, from two to four or more, will play in succession in a manner similar to the playing of other games:

The players may determine the order of entering the game by casting lots or by any other well understood procedure. The first player to enter will place his man on the starting point E and will snap the same by any suitable means, as by the use of his thumb and finger, toward the station H numbered 1 as his first goal. If the man is received in station 1 the same player is entitled to snap for the next station or number 2, following the course indicated by dotted lines or arrows, and he may continue playing as long as the result of each play is the landing in or at each goal or station aimed at. If and whenever a man in play stops on the central station I, such man is out of the game, the play is lost, and when the next turn comes he must start from the beginning.

When the first player has failed to reach the goal aimed at the second player starts in a similar manner from the point E and he will have in mind the following of the same course as above indicated, beginning with the station 1 and thence to the other consecutively numbered stations. Any succeeding player will have the option of going either directly to the next numbered station or snapping a preceding player's man if by so doing he may knock the preceding

player's man out of favorable position, and after having so struck an opponent's man the man then in play may be snapped again, either for the next station in order or for 5 the man of another competitor, but it is not permissible for one player to play on the man of any other player more than once until after having made a succeeding station. If a player is able to strike a competitor's man and thereby land it in the 10 central station I he has such privilege, thereby knocking out his competitor. The first player who succeeds in reaching goal 10 will then immediately have the right to retrace 15 his steps by snapping to or toward station 9 and thence to 8 in turn as before described until he reaches station 1 when the game is won by him. Any player whose man lands in the circle C must on his next play 20 start from the starting point E or F nearest to where his man has landed in the circle C and of the color corresponding to the color of the dwell G nearest to which the man was so landed. For example if the player's 25 man should be landed at the point J', such player on his next turn would start from the point F', while if his man had landed in the same arc shaped space but nearer the blue section of the dwell adjacent to the 30 starting point F' he would start next from the point E', aiming in each case however for his next station or goal in order or his opponent's man. It shall be regarded out of order for any player to knock an opponent's 35 man entirely off the board. The player so offending shall be regarded as out and can

only play on his next turn, beginning at the beginning. In the playing of this game it will be considered proper for the players to move freely from one side of the board to 40 another or around it if necessary for the purpose of making any desired play, or if more convenient the board itself may be turned so as to afford the best facility for any player whose turn it is to play, thereby 45 relieving him from the necessity of standing or walking around the board or table. For this purpose the board may be so made as to swing freely around its center as a pivot. 50

I claim:

1. The herein described game comprising a board having formed thereon a plurality of concentric fields, the innermost of which is provided with a series of consecutively numbered spaced stations, the outermost 55 field having a plurality of starting points differently indicated, a plurality of differently colored men for use by as many different players in succession to be started from the aforesaid starting points, and a series of dwells arranged in the remaining field of the board, each of the dwells comprising a plurality of colors corresponding to the colors of the starting points and with which they have correlation as to location and color. 60

2. A device as set forth in claim 1 in which the dwells are equally spaced and having arranged adjacent to the inner ends thereof respectively a like number of stations of the innermost field. 65

In testimony whereof I affix my signature.
JOSEPH GRECO.
